US00D577682S

(12) **United States Design Patent**
Amidon

(10) **Patent No.:** US D577,682 S
(45) **Date of Patent:** ** *Sep. 30, 2008

(54) **OPEN COMPRESSION-TYPE COAXIAL
CABLE CONNECTOR**

(75) Inventor: **Jeremy Amidon**, Marcellus, NY (US)

(73) Assignee: **John Mezzalingua Assoc., Inc.**, East Syracuse, NY (US)

(**) Term: **14 Years**

(21) Appl. No.: **29/299,889**

(22) Filed: **Jan. 7, 2008**

(51) **LOC (8) Cl.** 13-03

(52) **U.S. Cl.** D13/151; D13/154; D13/133

(57) **CLAIM**

The ornamental design for an open compression-type coaxial cable connector, as shown and described.

DESCRIPTION

FIG. 1 is a perspective view of an open compression-type coaxial cable connector, in an open position, showing my new design;

FIG. 2 is a side elevation view thereof, with the opposite side elevation being a mirror image thereto;

FIG. 3 is a top plan view thereof; and,

FIG. 4 is a bottom plan view thereof.

The broken line portion of the figure drawings is included to show unclaimed subject matter only and forms no part of the claimed design.

1 Claim, 4 Drawing Sheets

FIG. 1

FIG. 2

FIG. 3

FIG. 4
